APPLICATOR FOR SHOE POLISH

George M. Kendall, Peterborough, N. H.

Application December 14, 1944, Serial No. 568,133

3 Claims. (Cl. 15—108)

1

This invitation relates to applicators and polishers and more particularly to a polisher which is adapted to dispensing and applying shoe polish pastes of various kinds and similar materials.

It is an object of the invention to provide a combination holder, applicator and polisher which is efficient and convenient to use, which is attractive to look at, and which provides for more satisfactory dispensing of polishes, pastes and similar materials. Other objects of the invention will appear from the following description of the drawings and discussion relating thereto.

In the accompanying drawings:

Fig. 1 is a plan view of the polishing kit of the invention;

Fig. 2 is a vertical cross section taken on the line 2—2 of Fig. 1;

Fig. 3 is an enlarged fragmentary view of the front end of the polishing kit;

Fig. 4 is a view in front elevation; and

Fig. 5 is a rear elevational view of the device.

The device generally includes a holder in which may be supported a tube of polishing material, openings for permitting passage of the paste from the tube and holder, a tongue member for closing the opening in the holder and in the tube, and a rocker arm at the top of the holder for actuating the said tongue member. The holder is provided at its under side with a polishing material, and at the forward end of the holder there is provided an applicator which is arranged in a position adapted to receive paste as it is brought from the discharge hole of the tube by the tongue.

Referring more in detail to the drawings, numeral 10 indicates a holder and 12 refers to a rocker arm pivotally mounted at the top of the holder. The members 10 and 12 are made of any suitable material such as plastic, metal, wood, or other substances. As may be observed from an inspection of the drawings, these members are preferably shaped to offer a pleasing appearance and to fit comfortably in the hand of the user, the contour of a transverse section being oval-shaped for this purpose, as is more particularly indicated in Figs. 4 and 5.

The rocker arm 12 may be pivotally mounted as on a pin 14 at the top of the holder and in a preferred arrangement is snugly fitted in a longitudinal channel extending along the top of the holder 10. A clearance 16 is provided between the bottom 18 of the rear portion of the rocker arm and the side 20 of the channel so as to permit the arm to pivot in a clockwise direction as viewed in Fig. 2. The arm 12 is resiliently main-

2

tained in its normal position shown in Fig. 2 by means of a spring 22.

The holder 10 is formed with a longitudinal bore within which may be fitted a tube or container 30 filled with a polish or paste of a consistency suitable for extrusion. The bore through the holder member is formed at its forward end with an edge 32 which serves as a stop for the tube when thrust into position from the rear end of the holder.

The forward end of the tube 30 is provided with a small hole 34 near its periphery for the removal of paste. This hole is opened by some means as by the removal of a cover immediately before the tube is inserted in the bore, and the tube is inserted in a position such that the hole 34 occurs adjacent to the lower side of the holder as indicated in Figs. 2, 3 and 4, and coincident with the opening in the forward end of the bore. The tube is kept from turning within the bore and the proper positioning of its hole 34 is assured by some suitable means, as for example a spring clip 37. I may also desire to employ a lug or a pin which passes transversely through the bore and engages against the tube. Various other means of securing the tube may be resorted to.

Both the open part of the front end of the bore and the hole 34 in the tube are normally closed and the latter substantially sealed by a tongue member 40 which is resiliently urged against the tube and is of a sufficient width to overlap the opening 34. This tongue may be constructed in any suitable way; for example it may be an integral extension of the arm, or as indicated in the drawings it may be a thin strip of spring metal covered with a pad of suitable material and having one end affixed to the arm and the other end bearing resiliently against the front end of the tube.

The tube, which is supplied as a replaceable unit, is provided with a longitudinally extending shaft 44, which is screw-threaded. One end of the shaft projects out beyond the rear end of the tube 30 and has a handle 46 secured thereon to permit rotation of the shaft. This handle may be colored to indicate type of paste within. The tube is normally fitted with a supply of paste 47, lying in front of a plunger member 50 which may be in the form of a disc screw-threaded on the shaft 44 and fitting closely against the inner periphery of the tube 30.

When the shaft 44 is rotated in the proper direction, the plunger 50 presses against the paste supply, forcing this material forwardly and out

of opening 34. Behind the plunger 50 is a stopper 52 of cork or other suitable material, which fits snugly within the container and around the shaft 44 to seal the tube and prevent the escape of volatile solvent materials from the paste and thus keeping the paste from thickening. A cover 36 rotating with the shaft and fitting loosely within the rear end of the container 30 serves as a bearing against transverse pin crimping or other construction.

At the under side of the holder 10 are secured an applicator or dauber 60, a spreader brush 61, and a polishing material 62. The polishing material is preferably formed of a soft substance such as soft bristles, lamb's wool, and the like. The applicator 60 is arranged adjacent to the forward end of the tube at a point just below the opening 34. The location of the dauber or applicator at this point is especially designed to cooperate with the tube and also with the tongue 40.

It will be observed that if the arm 12 is depressed, thus raising the tongue, and if the shaft handle 46 of the tube is then turned, the paste will be expelled; and upon release of the arm 12 the tongue will pass downward across the face of the tube with a wiping action, transferring the extruded paste to the edge of the applicator in a position convenient for transfer to a shoe or other article to be polished or treated. Thus the tongue member serves to aid in transfer of the expelled material from the tube to the applicator in a clean stroke, and the presence of excess material at the front of the holder is avoided. In carrying out this operation, the tongue member continues to perform its sealing effect with relation to the opening 34.

To use the device the operator holds it in his hand and bears against the rear end of the rocker arm 12 to pivot this member and raise its forward end. The tongue 40 is thereby lifted away from the hole 34, as has been diagrammatically illustrated in Fig. 3 of the drawings. While the tongue is in a raised position, the shaft 44 is rotated by turning the handle 46 which presses the plunger against the paste and causes some of this material to extrude from the hole 34. When a sufficient quantity of the paste has been extruded from the container, the arm 12 is released, forcing the tongue 40 downwardly into a sealed position over the opening in the container, and in so doing wiping the extruded paste from the container and conveying it to the forward edge of the applicator. The paste on the applicator may then be spread to desired points on a shoe or other article after which, if desired, the polisher 62 may be rubbed or applied to the shoe in the usual manner.

It will be seen that the device is compact and convenient to use since it combines a container of polish or paste, an applicator and polisher all in one unit and the applicator is arranged so that it naturally is in a position both to receive paste and apply it. The tongue insures a proper sealing action and elimination of loss of volatiles, at the same time transferring paste to the applicator and providing a means of removing excess amounts of paste from the face of the tube. It will also be noted that the tube is closed at all times except at the instant of use; and that due to the spring-impelled action of the rocker arm and tongue, it is at the same time exceedingly easy to obtain paste from the tube, and impossible to leave the tube open.

I may desire to resort to various other shapes 75

and sizes of holder, as well as other arrangements for combining the dauber with the applicator. I may also desire to modify the device by extending the spreader brush to a point adjacent to the opening in the forward end of the tube so that the spreader may function as both dauber and spreader.

While I have shown a preferred embodiment of my invention, it should be understood that various changes and modification may be resorted to, in keeping with the spirit of the invention as defined by the appended claims.

I claim:

1. A polishing kit comprising in combination a holder having a bore formed therethrough, a paste container detachably secured in the bore, said container having an opening formed at the lower front end thereof, means for forcing paste out of the said opening in the container, an arm pivotally mounted at the upper side of the holder, spring means for resiliently maintaining the front end of the arm against the holder, a tongue extending from the arm into a sealed position over the said container opening, said tongue adapted to assume a raised position upon movement of the arm, thereby to permit ejection of paste from the tube, an applicator secured at the under side of the holder adjacent to the opening in the container, and a polishing material attached at the under side of the holder and to the rear of the applicator.
2. A polisher comprising a holder having an applicator member secured at the front end thereof, a rocker arm pivotally mounted at the upper side of the holder, a container supported in the holder and formed with an opening near the perimeter of the end adjacent to the said applicator, a tongue member secured to the rocker arm and being normally held in sealed relation with respect to the opening, and means for expelling paste through the container and holder when the tongue is moved out of engagement with the front end of the holder.
3. As an article of manufacture, a device for applying paste-like materials comprising a holder, a dauber located at the forward end of the holder, a paste container detachably secured in the holder, said container having an opening lying closely adjacent to one side of the dauber, means for expelling paste through the opening, a tongue member supported on the forward end of an arm which is movably attached to the holder, the extremity of the tongue member lying closely adjacent to the dauber and being resiliently urged into sealed relation with the opening in the paste container, said extremity of the tongue in assuming a sealed position over the container opening being adapted to transfer paste material as it is emitted from the container upon adjacent edges of the dauber.
